UNITED STATES PATENT OFFICE.

JOHN C. FIDDYMENT, OF MOUNT GILEAD, OHIO, ASSIGNOR TO THE HYDRAULIC PRESS MANUFACTURING COMPANY, OF MOUNT GILEAD, OHIO.

PRESS.

Application filed July 27, 1923. Serial No. 654,249.

To all whom it may concern:

Be it known that I, JOHN C. FIDDYMENT, a citizen of the United States, and resident of Mount Gilead, in the county of Morrow and State of Ohio, have invented certain new and useful Improvements in Presses, of which the following is a specification.

This invention relates to a continuous press for use in pressing oil seeds, nuts, soy beans, copra, and in general any substance from which fat, oils or other fluid may be expressed.

An object of the invention is to provide such a press which will have a constant rotation in one direction, and will handle various materials efficiently and rapidly.

Another object is to provide means for draining out the liquid rapidly as the material is pressed and finally disposing of the material remaining after the extraction of the fluid in such a manner that the press may operate continuously and at the same time exert sufficient pressure to express the fluid thoroughly.

Other objects will be apparent from the following detailed description and the appended claims.

In the drawings:

Figure 1 is a top plan view of the press and operating means therefor.

Figure 2 is an end view.

Figure 3 is a section on the line 3—3 of Figure 1, showing the means for feeding material to the press proper.

Figure 4 is a longitudinal section through the press proper.

Figures 5, 6, 7 and 8 are sections on the lines 5—5, 6—6, 7—7 and 8—8, respectively, of Figure 4.

Figure 9 is a development of a portion of the feeding and pressing mechanism.

The various members of the press are carried on a suitable base 1 by means of appropriate brackets or supports. Mounted in brackets 2 and 3 is a shaft 4 having a pulley 4' driven from any suitable source of power. The shaft 4 carries a pinion 5 which meshes with a large gear 6 carried by a short shaft 7 mounted in bearings in a bracket 8. The shaft 7 also carries a small pinion 9 which meshes with a large gear 10 carried by a shaft 11 mounted in bearings in brackets 12 and 13. The shaft 11 also carries a pinion 14 which

meshes with a large gear 15 carried by the main press shaft 16. The purpose of this train of gearing is to reduce the speed of rotation from many revolutions per minute of the shaft 4 to a few revolutions per minute of the shaft 15. It is obvious that any desired form of gearing may be used which will permit the attainment of this object.

Outside the bearing bracket 2 the shaft 4 is provided with sprocket wheel 17 and a sprocket chain 18 runs around this wheel and around a sprocket wheel 19 on a shaft 20 mounted in bearings in brackets 21 and 22. The shaft 20 carries a sprocket wheel 23 around which passes a sprocket chain 24 which also drives a sprocket wheel 25 fast on a shaft 26 mounted in bearings 27 and 28 in a standard or bracket 29. The shaft 26 has a bevel gear 30 which meshes with a larger bevel gear 31 on the end of a shaft 32. This shaft 32 is provided with a worm 33 which rotates within a cylindrical feed passage 34 with which communicates a feed hopper 35.

A generally cylindrical casing 36 is supported in standards which rest upon the base 1 and is lined with a hardened steel bushing 37. At one end an extended bearing 38 attached to the casing 36 supports one end of the shaft 16, while the other end of this shaft is supported by a series of thrust bearings 39 carried by a standard 40 which is bolted to the standard 41 integral with or supporting the casing 36. Within a portion of the casing 36 the shaft 16 is provided with a worm thread 42, the periphery of which is spaced a slight distance only from the bushing 37. In order that there shall be no opportunity for the shaft 16 to spring to one side, the screw thread is provided on its periphery at intervals with a metal wear plate 43 (see Fig. 8) which engages the bushing. The shaft 16 is tapered as shown in Fig. 4, and the spaces between the outer surface thereof and the bushing 37 become smaller as the material being pressed approaches the discharge end.

The shaft 16 has a hollow center 44 and the screw thread 42 is provided with passages 45 which extend to the center 44 from the periphery of the thread. The general arrangement of these passages is shown in Figure 8. Since the periphery of the screw

thread is spaced from the bushing 37 as stated above, the oil or other liquid being expressed will flow into these spaces and through the passages 45 to the center 44 and 5 may be collected in any suitable manner from the end of the shaft. The space between the periphery of the screw thread 42 and the bushing 37 is not sufficient to permit the solid materials to pass therethrough, but 10 the fluids will find an exit in this manner.

The standard 40 has a cylindrical enlargement 46 connected to the casing 36 near its exit, and within this enlargement the shaft 16 has an external screw thread 47 upon which 15 screws a collar 48 provided with openings 49 for engagement by an appropriate tool. By this means the position of a loose collar 50 is adjusted, and this collar has a beveled end 51 to cooperate with the beveled exit end 20 52 of the casing 36. The solids are ejected through the annular passage between the collar 50 and the end of the casing. The size of this opening may be varied in accordance with the material being treated 25 or the degree of pressure to which it is desired to subject the material. The enlargement 46 is provided with top, bottom or side openings through which the ejected material may pass.

30 At one end the casing 36 has its lower side cut away and communicates with the upper cut away side of the casing 53 which is not quite cylindrical in shape. The casing 36 and casing 53 are shown as being 35 made integral but of course this is not essential. Within the casing 53 is a two part bearing member 54 in which is mounted a shaft 55 as shown in Figure 4. Since the casing 53 is not entirely cylindrical, a 40 lune shaped member 56 is placed in the bottom thereof, having its upper surface curved to correspond with the bearing 54. This is adjustably held in position by a screw 57 as shown in Figure 4, and furnishes means for the exact adjustment of 45 the bearing 54. Also when it is desired to remove the shaft 55 and parts carried thereby, the screw 57 is removed and the lune shaped member 56 may be removed endwise. This will permit the bearing 54 and 50 shaft 55 to drop down to a position from which it may also be removed through the open end of the casing 53. This bearing 54 also prevents thrust tending to force sides 55 of B and C against walls of channels E and F.

At one side there is an opening through the casings 36 and 53 at their juncture with which communicates the feed passage 34. 60 The material is fed from the hopper by the screw 33 through the passage 34 into the casings 36 and 53 at their juncture, and is there received by feed mechanism which transmits it to the screw 42.

65 This feed mechanism is of peculiar char-

acter and is illustrated in Figs. 4 to 7 and 9. The shaft 55 is provided with three ring like members A, B and C. The member A has six teeth *a* as shown, while the members B and C have three cut outs *b* 70 and *c* respectively. Each of the three cut outs is approximately one-sixth of the circumference in extent, and the two members B and C are located on the shaft 55 in such relation that a cut out in one member comes 75 opposite the solid portion of the other. The three members A, B and C are separated from each other lengthwise of the shaft 55 by portions of the bearing 54 as shown clearly in Figure 4.

The shaft 16 has three portions D, E and F which cooperate with the members A, B and C respectively. The member D has two cut outs *d*' diametrically opposite and separated by rib portions *d*. Each cut out is approximately one-sixth of the circumference in extent. The portions E and F are channels formed by ribs on the shaft, and each has a projection *e* and *f* respectively which is or may be about one-sixth 90 of the circumference, the projections *e* and *f* being arranged so that they always extend in opposite directions.

The shaft 55 is turned by the cooperation 95 of the projections *e* and *f* with the cut outs *b* and *c* respectively. The members D and A cooperate to hold the shaft 55 against movement except at two points in the revolution of the shaft 16. Whenever a cut out *d*' comes opposite a tooth *a*, either the projection *e* is in position to cooperate with a cut out *b* in the member B or the projection *f* is in position to cooperate with a cut out *c* in the member C. In either case the shaft 55 is given a one-sixth revolution. 100 While the rib *d* is in the position shown in Figure 5, where it practically contacts with two teeth *a*, the member A is held against movement. It is evident that the shaft 55 is driven in this manner step by step from the constantly rotating shaft 16 and is given one complete revolution by three revolutions of the shaft 16.

In Figs. 5, 6 and 7, as well as Fig. 3, 110 the shaft 16 is revolving counter clockwise. The material is fed by the screw 33 into the channel in the member E at the point X, and the projection *e* is moving away from the incoming material which fills up the channel behind the same until the projection *e* has made nearly a revolution, when the material passes through a cut out behind this projection or stop *e* into the next channel. In similar manner the material 115 thus passed into the second channel is passed through another cut out in the channel F. The channels E and F are separated by a channel as shown in Figure 4 which comes opposite the wide bearing member between the members B and C. Finally the 120 125 130

material passes through a cut out from the channel F to the screw member 42.

Figure 9 is a development of the portion of the shaft 16 having the members E and F and intermediate channel thereon, and the material introduced at the point X follows the dot and dash line as shown from the point of introduction through the cut outs from one channel to the succeeding one and finally to the screw. Some material will enter the cut outs b and c and be carried around, but this is of no particular importance. In Figure 6 for example, while the stop e is travelling substantially one half of a revolution, the member B is stationary, and the periphery thereof engages the bottom and sides of the channel E closely enough to prevent any of the material which has been previously introduced and is now on the pressure side of this stop e from coming back to the starting point. It is therefore forced into the adjacent channel through the cut out in the walls of the first channel as described. The same action takes place in the channel F. These stops formed by the projecting portions of the members B and C substantially fill the channels and cannot be displaced in any manner. In Figures 6 and 7, for example the point marked H acts as a stop for preventing the material from revolving with the shaft or passing this point. The projections e and f can pass through b and c or b' and c', but the material cannot follow, and while f is passing through c the channel is blocked by B, so that if any material should get through while f is passing it cannot get out into the feed. The material is therefore caused to travel along under pressure to a point where it is taken up by the screw.

It may be noted that this feed mechanism may be used with other types of expressing apparatus, and is in no way limited to the specific form here shown, although it cooperates therewith.

The bolts 59, in Figure 1, may be used as jack screws to take the casing off of the shaft if the machine stalls. One end of these screw bolts is fixed and the other is screw threaded and passes through the lugs as shown.

Means may be provided if desired for varying the rate of feed of the screw 33 since the compression is affected by the amount of material fed into the first channel. It is obvious that detail changes may be made in the precise form and arrangement of various elements without departing from the spirit of the invention and it is to be understood that the invention is limited only by the scope of the appended claims.

I claim as my invention:

1. In a press, a press chamber provided with a screw shaft, a series of ribs forming channels on said shaft near the inlet end of

the chamber, means for constantly rotating said shaft, a countershaft, members thereon cooperating with said channels, and means whereby the countershaft is rotated step by step by the rotation of the screw shaft. 70

2. In a press, a press chamber, a shaft therein, a countershaft adjacent thereto, means for rotating the shaft continuously, and means operated by the continuous rotation of the shaft for the intermittent rotation of the countershaft. 75

3. In a press, a press chamber, a shaft therein, ribs at one end of the chamber on said shaft forming channels, said ribs having cut outs forming means of communication between each two adjacent channels, a countershaft adjacent thereto, means for intermittently rotating said countershaft, means on said countershaft working in said channels, and obstructions in said channels 85 causing the material to be forced through said cut outs. 85

4. In a press, a press chamber, a shaft therein, ribs at one end of the chamber on said shaft forming channels, said channels 90 communicating each with the adjacent channel, obstructions in said channels adjacent the points of communication, a countershaft, means on the countershaft working in said channels, means for rotating said shaft, and 95 means for intermittently rotating the countershaft from the rotation of the shaft. 95

5. In a press, a press chamber, a shaft therein, ribs at one end of the chamber on said shaft forming channels which communicate with each other through cut outs in said ribs, a countershaft, stops on said countershaft engaging in said channels, obstructions in said channels, and means for rotating the shaft whereby the obstructions and 105 stops cooperate to feed the material from one channel to the subsequent one. 100

6. In a press, a press chamber, a shaft therein, means at one end of the chamber on the shaft forming channels communicating 110 with each other, obstructions in said channels, a countershaft, stops on the countershaft engaging in said channels, means for rotating the shaft continuously, and means whereby the obstructions cooperate with the 115 stops to rotate the countershaft intermittently. 110

7. In a press, a press chamber, a bushing therefor, a shaft within said chamber, a screw thread on said shaft the periphery of which is slightly spaced from said bushing, and metal wear plates provided at intervals on the periphery of said screw thread and contacting with the bushing. 120

8. In a press, a press chamber, a bushing 125 therefor, a shaft within said chamber, a screw thread on said shaft the periphery of which is slightly spaced from said bushing, drain openings extending to the periphery of said screw, and metal wear plates pro- 130

vided at intervals on the periphery of said screw thread and contacting with the bushing.

9. In a press, a press chamber having a beveled end, a shaft within said chamber, a collar on said shaft having a bevel forming with the beveled end of the chamber an an-

nular exit for the solids, and a member screw threaded on said shaft and engaging the collar to adjust the position of the same. 10

In testimony whereof, I have hereunto subscribed my name.

JOHN C. FIDDYMENT.
